UNITED STATES PATENT OFFICE.

FREDRICK PACKARD, OF BROCKTON, MASSACHUSETTS.

SHOE.

SPECIFICATION forming part of Letters Patent No. 293,064, dated February 5, 1884.

Application filed August 24, 1883. (No model.)

To all whom it may concern:

Be it known that I, FREDRICK PACKARD, a citizen of the United States, residing at Brockton, in the county of Plymouth and State of Massachusetts, have invented an Improvement in Shoes, of which the following is a full, clear, and exact description, reference being had to the accompanying drawings, making part of this specification, in which—

10. Figure 1 is a plan of a shoe having my improvement applied thereto. Fig. 2 is a side elevation of the same. Fig. 3 is a rear elevation of the same.

My invention relates to an improvement in 15 that class of shoes which are provided with elastic gores at the sides, and has for its object to facilitate the operation of drawing on and pulling off the shoe; and my invention consists in a shoe having its leg portion provided 20 on both sides with an elastic gore extending around the rear of such leg portion and projecting above the inelastic heel portion thereof, whereby increased elasticity is afforded at the rear of the leg portion, as hereinafter set forth.

25. In the said drawings, A represents my improved shoe, the leg portion b of which is provided on each side with an elastic gore, B. The two gores B B are formed of a single piece of 30 suitable elastic fabric united by a portion, c, which extends around the rear of the leg of the shoe and projects above the inelastic heel portion d thereof, the rear pulling-loop, e, being preferably attached to the heel portion d 35 and entirely disconnected from the elastic portion c.

Instead of forming the elastic portion B B c of the leg portion of the shoe of a single piece of material, as above described, it may, if preferred, be made of two or more pieces united 40 by a seam or seams.

45. By providing a shoe with an elastic portion, c, extending from the side gores around the back of the leg portion, above the inelastic part thereof, as described, the rear portion of the leg is enabled to yield backward to such an extent in drawing on the shoe that the latter operation is rendered much easier than heretofore, while a comfortable fit at the ankle

is also insured; and as in the operation of 50 drawing on a shoe the principal portion of the strain is exerted at the rear, and not at the front of the leg portion, the placing of the elastic portion c at the rear instead of at the front of the leg portion, renders it possible to afford 55 the desired elasticity at the exact point required to secure the best results. Furthermore, by locating the elastic portion c at the rear of the leg portion the front of the leg portion is left in proper condition for attaching 60 thereto an imitation of lacing or buttoned front or other fancy work, which should extend to the top of the leg portion, to give the shoe the required finish, which could not be accomplished with the elastic portion placed in front. 65

I am aware that a shoe has been made having a vertical elastic gore at the heel extending from the top to the bottom of the leg portion, and sustained by a strap or straps permanently connected therewith, as described in 70 the United States Patent of L. Graf of January 4, 1881, No. 236,323. I therefore lay no broad claim to an elastic gore applied to the heel of a shoe or to any of the details of construction shown in the aforesaid patent of Graf. 75

What I claim as my invention, and desire to secure by Letters Patent, is—

1. A shoe having its leg portion provided on both sides with an elastic gore extending around the rear of such leg portion and projecting above the inelastic heel portion thereof, substantially as and for the purpose set forth.

2. In a shoe, the combination, with the leg portion, of the two elastic side gores, B B, 80 united by an elastic portion, c, extending around the rear of such leg portion and projecting above the inelastic heel portion thereof, all constructed and arranged to operate substantially in the manner and for the purpose described.

Witness my hand this 22d day of August, A. D. 1883.

FRED. PACKARD.

In presence of—

P. E. TESCHEMACHER,
W. J. CAMBRIDGE.
